(57) **CLAIM**

The ornamental design for eyeglass frames, as shown and described.

DESCRIPTION

FIG. 1 is a front, right, top perspective view of a first embodiment of eyeglass frames, showing the new design; FIG. 2 is a rear, left, bottom perspective view thereof; FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right, top perspective view of a second embodiment of eyeglass frames, showing the new design; FIG. 10 is a rear, left, bottom perspective view thereof; FIG. 11 is a front elevation view thereof;

FIG. 12 is a rear elevation view thereof;

FIG. 13 is a left side view thereof;

FIG. 14 is a right side view thereof;

FIG. 15 is a top plan view thereof; and,

FIG. 16 is a bottom plan view thereof.

The broken lines of uneven length illustrate the boundary of the claimed design and form no part thereof. The broken lines of even length shown in the drawings illustrate portions of the component of the eyeglass frames that form no part of the claimed design.
